UNITED STATES PATENT OFFICE

156,365

COIN BANK

Thomas D. O'Malley, Wilmette, Ill.

Application November 5, 1947, Serial No. 142,311

Term of patent 3½ years

(Cl. D34—11)

To all whom it may concern:

Be it known that I, Thomas D. O'Malley, a citizen of the United States, and resident of Wilmette, in the county of Cook and State of Illinois, have invented a new, original, and ornamental Design for a Coin Bank, of which the following is a specification, reference being had to the accompanying drawing, forming a part thereof.

Fig. 1 is a front elevational view of the coin bank, showing my new design.

Fig. 2 is a side elevational view of the same.

Fig. 3 is a top plan view of the same.

I claim:

The ornamental design for a coin bank, substantially as shown.

THOMAS D. O'MALLEY.
